UNITED STATES PATENT OFFICE.

WILHELM SCHALLER, OF NEW YORK, N. Y.

ASH-CART.

SPECIFICATION forming part of Letters Patent No. 707,163, dated August 19, 1902.

Application filed June 19, 1902. Serial No. 112,288. (No model.)

To all whom it may concern:

Be it known that I, WILHELM SCHALLER, a citizen of Germany, residing at New York city, county and State of New York, have invented certain new and useful Improvements in Ash-Carts, of which the following is a specification.

This invention relates to a cart or wagon for removing ashes and garbage and which is so constructed that dust and cinders will be prevented from escaping during the loading and carting. In this way the objectionable exposure of persons to the flying dust and dirt from ash-carts will be obviated.

15 In the accompanying drawings, Figure 1 is a side view of an ash-cart embodying my invention, showing the lid raised; Fig. 2, a similar view with the lid lowered; Fig. 3, a front view of the cart; Fig. 4, a section 20 through the upper part of the cart-body; Fig. 5, a face view of the folding lid; Fig. 6, an end view thereof; Fig. 7, a perspective view of the upper forked catch, and Fig. 8 a detail of the lower spring-catch.

25 The letter *a* represents the body of a cart or wagon adapted for the reception of ashes, garbage, or similar refuse matter. From the body *a* projects upwardly a communicating dome or chamber *a'*, provided with an open 30 side and an inwardly-folding door *a²*. This door is hinged to the top of the dome *a'* at *a³* and normally closes the open side of the latter by gravity. To the lower end of dome *a'* is hinged at *b'* an outwardly-folding lid *b*, 35 which when swung up also closes the open side of the dome.

The lid *b* is provided with means for attaching to its inner face an ash-can or garbage-receptacle *c*, which is secured to the lid when 40 the latter is swung downward or into its open position, Figs. 2 and 3. These means are shown to consist of a pair of brackets *d*, constituting a base and having a straight upper side and an inclined lower side *d'*. Between 45 the brackets *d* there is supported in bearings *e* a bent laterally-folding catch *e*, which is normally drawn upward by a spring *e²*. When this catch is swung sidewise, Fig. 5, its lower horizontal arm will impinge against the inclined plane *d'* of one of the brackets *d*, so 50 that the catch is depressed against the action

of spring *e²*. When the catch is swung forward and has cleared the inclined plane *d'* it will be drawn upward by the spring.

The upper edge of the can *c* is adapted to 55 be engaged by a pair of forks or catches *f*, carried by a frame *f*, Fig. 7, which in turn is secured to the lid *b*. To the frame *f* is hinged by a pintle *g'* a cover *g* for closing the can *c*. This cover is held against the can by a weak 60 spring *g²*, coiled around pintle *g'*, and bearing with one end upon the cover, Fig. 6.

The lid *b* is locked in its closed position by a hook *b²* and may be manipulated by a handle *b³*.

65 The ashes within the cart may be leveled by a rake introduced through a normally covered opening *h*, and they are removed in a suitable manner, the drawings showing the cart to be provided with a folding top *i* back 70 of the dome *a'*.

In use the hook *b²* is opened and the lid *b* swung down by handle *b³*, the door *a²* preventing meanwhile the escape of dust from the cart. The can *c* is lifted upon the brackets *d*, so that its upper edge is grasped by the forks *f*, and then the spring-catch *e* is swung forward to lock the can in position, the mouth of the can being closed by the spring-influenced cover *g*. As the lid *b* is swung up the 80 can upon striking the door *a²* will open the same inward to give access to the can; but the opening so formed will be at once closed by the lid *b*, which will now prevent the escape of the ashes. When the lid *b* is entirely 85 closed, the can *c* will be reversed and its contents will be discharged, the cover *g* swinging open against the action of weak spring *g²*. After the can has thus been dumped the lid *b* is opened, the can removed, and the operation may be repeated.

90 It will be seen that by my invention the manipulation of the can is simplified and that the cart is always closed by either one of two lids which prevent at all times the escape of 95 dust.

95 My improvement may be applied to the wagons and carts now in use by supplying the same with a cover carrying the dome and double folding lids.

100 What I claim is—

1. An ash-cart provided with an inwardly-

swinging door, an outwardly-swinging lid, and means for attaching an ash-can to the lid, substantially as specified.

2. An ash-cart provided with an inwardly-swinging door hinged to the top of the cart-body, an oppositely-hung outwardly-swinging lid hinged in front of said door, and means for attaching an ash-can to the lid, substantially as specified.

10 3. An ash-cart provided with a hinged lid, a bracket having an inclined lower side, and a bent spring-influenced folding catch adapted to engage said side, substantially as specified.

15 4. An ash-cart provided with a hinged lid, a bracket, a bent spring-influenced folding

catch adapted to engage the bottom of an ash-can, a second catch adapted to engage the top of said can, and a spring-influenced cover adapted to close the can, substantially as specified.

5. An ash-cart provided with an inwardly-swinging door, an outwardly-swinging lid, means on the lid for supporting an ash-can, and a spring-influenced cover for closing said can, substantially as specified.

Signed by me at New York city, New York, this 18th day of June, 1902.

WILHELM SCHALLER.

Witnesses:

WILLIAM SCHULZ,
F. v. BRIESEN.
